UNITED STATES PATENT OFFICE

160,254

KEY HOLDER OR THE LIKE

Charles F. Degner, Chicago, Ill., assignor to
Martha Lee Degner, Boonville, Mo.

Application November 15, 1947, Serial No. 142,561

Term of patent 14 years

(Cl. D17—14)

To all whom it may concern:

Be it known that I, Charles F. Degner, a citizen of the United States, residing at Chicago, county of Cook, State of Illinois, have invented a new, original, and ornamental Design for a Key Holder or the like, of which the following is a specification, reference being had to the accompanying drawing, forming a part hereof.

In the drawing:

Fig. 1 is a side elevation of a key holder showing my new design.

Fig. 2 is a similar elevational view showing the opposite side of the key holder from that shown in Fig. 1.

Fig. 3 is an edge view of the key holder.

I claim:

The ornamental design for a key holder or the like, as shown.

CHARLES F. DEGNER,
